ALONZO ASHCRAFT, OF FORT SMITH, ARKANSAS.

AUTOMATIC PRESSURE-RETAINING VALVE.

No. 833,570.

Specification of Letters Patent.

Patented Oct. 16, 1906.

Application filed November 29, 1905. Serial No. 289,616.

To all whom it may concern:

Be it known that I, ALONZO ASHCRAFT, a citizen of the United States, residing at Fort Smith, in the county of Sebastian and State 5 of Arkansas, have invented a new and useful Improvement in Automatic Pressure-Retaining Valves, of which the following is a specification.

My invention relates to improvements in 10 automatic pressure-retaining valves and is designed to take the place of the well-known hand-operated pressure-retainer, its object being to automatically retain a predetermined amount of braking pressure in the 15 brake-cylinder of a car, locomotive, or tender, and to produce a device which shall be absolutely under the control of the engineer.

A further object is to produce a device whereby the engineer may when on a long 20 downgrade by simply moving a conveniently-located lever in the engine-cab put all retainers in operation, so that when he applies the brakes and again releases ten or fifteen pounds of braking pressure will be re- 25 tained in the brake-cylinder, the amount desired being regulated by a Westinghouse or other reducing-valve conveniently located in the engine-cab. The hand-retainers now in use retain fifteen pounds pressure. This 30 amount may be varied, however, as before stated, by a reducing-valve, which will be explained later.

To these ends my invention consists in certain novel features of construction, arrangement, and combination of parts, as will be hereinafter fully described, and pointed out in the claims, reference being had to the accompanying drawings, in which—

Figure 1 is a sectional view of the device 40 when the retaining-valve is not in use. Fig. 2 is a similar view as in use.

In carrying out my invention I use a valve-casing A, having differential areas chambers A' and A'', one of said casings being placed 45 under each car, connected at their lower ends with a pipe B, preferably one-half inch in diameter, and at their upper ends by a pipe C with the exhaust-port of the ordinary triple valve. The pipes B, which extend the full 50 length of each car, are connected at each end by the ordinary air-hose and couplings, forming a continuous train-line pipe. The pipe B also extends into the locomotive-cab, where it is connected with the main reservoir.

Within the casing is fitted a piston D, that is provided with the heads D' and D'', prefer-

ably of different areas. The larger head D' fits snugly in the lower chamber A' and the upper head D'' fits in the same manner in the upper chamber A'', the two heads being connected, as stated, by the common piston-rod. In the side wall of the upper chamber near its lower end is drilled a port or opening A⁵, which communicates with the atmosphere.

Within the pipe B and conveniently located in the engine-cab is placed an ordinary three-way cock E, provided with a handle E' and fitting within the casing E'', which is provided with an exhaust-port or bleeder E³ to the atmosphere. The three-way cock is provided with the passages E⁴ and E⁵. At a suitable point in the pipe B in the engine-cab between the three-way cock and main reservoir is placed a reducing-valve of any suitable construction.

When the retainers are not in use, the handle E' of the three-way cock is to be left parallel with the casing E'' of the three-way cock, allowing passage E⁵ to coincide with pipe or passage B and passage E⁴ to coincide with 80 passage or port E³, thereby cutting the flow of air from main reservoir and opening pipe B to the atmosphere. While the handle E' is in the above-mentioned position, the piston-heads D' and D'' of the automatic retainer-valve will be down in position, as shown in Fig. 1. When the brakes are released, the pipe C being connected with the triple-valve exhaust-port, exhausted air from the brake-cylinder will pass through pipe C into chamber A'', and thence to the atmosphere through port A³, which will allow all the air to exhaust from the brake-cylinder and result in a full release of the brakes. Now on a long 90 downgrade the engineer wishes to retain, say, fifteen pounds braking pressure in all 95 brake-cylinders after the brakes have been released. This retained pressure is wanted and on mountain roads is absolutely necessary for the purpose of holding the train in check until the auxiliary reservoirs are fully recharged. The handle E' is then placed at right angles to casing E'' in the position shown in Fig. 1, and as there is a reducing-valve located at the point X between the three-way 100 cock and the main reservoir he sets to reduce pressure to five pounds. Then air-pressure to the amount of five pounds to the square inch is now allowed to pass through passage E⁴ and pipe B under the cars and into chamber A' of the retainer-valve, forcing piston-head D' to the upper end of chamber A', caus-

ing piston-head D^2 to pass above the port A^3 , thus cutting off communication between the pipe C and the atmosphere. The large piston-head D' has an area of three square inches, 5 and there now being a pressure of five pounds to the square inch in chamber A' there will be a total pressure of fifteen pounds, tending to hold the piston-head D' up in the position just mentioned. Now when the brakes are set 10 there is about fifty pounds air-pressure to the square inch in the brake-cylinders. The engineer releases the brakes, and this pressure of fifty pounds is permitted to pass by means of the triple valve into the pipe C and thence 15 to the retainer-valve where it comes in contact with the piston-head D^2 . This piston-head has an area of one square inch. Hence there is now a total pressure of fifty pounds on the small head D^2 and a total pressure of fifteen 20 pounds under the lower piston-head D' . The pistons will accordingly be forced downwardly to the position shown in Fig. 1, allowing air to pass through port A^3 to the atmosphere until pressure in chamber A^2 is reduced to fifteen 25 pounds, when the pistons will be equally balanced, and further reduction in the chamber A^2 , which will continue as long as port A^3 is open, will allow pressure in chamber A' to force the pistons upwardly, carrying the piston-head D^2 to the upper end of chamber A^2 , 30 cutting off port A^3 , thereby retaining the remaining pressure in the brake-cylinder. Now to cut the retainer out of service the handle E' is moved parallel with the body of the casing 35 of the three-way cock, which not only cuts off air coming through the reducing-valve, but as passage E^5 now coincides with the passage or pipe B and passage E^4 with outlet-port E^3 air is permitted to escape from chamber A' and 40 pipe B to the atmosphere, which allows piston D^2 to assume the lowermost position. (Shown in Fig. 1.)

It is not absolutely necessary that the piston-heads shall be differential in area, as they 45 may be of equal area; but the advantage of having the lower head of three times the area of the one in chamber A^2 is that it is only necessary to draw on the main reservoir for one-third the amount of air-pressure that is desired 50 to be retained in the brake-cylinder. The operation of cutting in and cutting out all of the retainers, and they may be left on as long as desired, has only cost an expenditure of main-reservoir air of a volume equal to the 55 combined volume of the one-half-inch pipe and chamber A' at five pounds pressure. If

the piston-heads were of equal size, it would have cost approximately three times as much as it did with the pistons related as shown.

Having thus described my invention, what 60 I claim as new, and desire to secure by Letters Patent, is—

1. In a fluid-pressure brake system comprising a main reservoir and triple valve, the combination with a line of piping connecting 65 said reservoir with the exhaust of said triple valve, of a valve-casing interposed in said casing intermediate the main reservoir and triple-valve exhaust, said casing comprising two chambers, a solid double-headed piston-valve fitted to reciprocate in said casing within the two chambers, and a reducing-valve interposed in the piping between the 70 main reservoir and the double-headed piston.

2. In a fluid-pressure brake system, 75 comprising a main reservoir and a triple valve, the combination with a line of piping connecting the reservoir with the exhaust of the triple valve, of a valve-casing interposed in said piping between the triple valve and main reservoir, said casing comprising two chambers of different areas, the smaller-area chamber being the nearer to the triple-valve exhaust, and having an outlet to the atmosphere at or near its lower end, a piston-rod within said 80 valve-casing, solid piston-heads at each end of said piston-rod of different area, the smaller piston-head fitting in the smaller chamber, a reducing-valve interposed in the piping between the valve-casing and the main reservoir, 85 and means for cutting in and out the valve-casing with the main reservoir.

3. In a fluid-pressure brake system, comprising a main reservoir and a triple valve, of a line of piping connecting the reservoir with 95 the exhaust of the triple valve, a valve-casing interposed in said piping between the triple valve and the main reservoir, said casing consisting of an upper and a lower chamber, the upper chamber having an outlet-port to the atmosphere at or near its lower end, a double-headed solid piston, fitted to slide in said upper and lower chambers, three-way cock interposed in the piping between the retainer-valve and the main reservoir, 100 and a reducing-valve interposed between the three-way cock and the main reservoir.
